UNITED STATES PATENT OFFICE

EDWARD FERRISS, OF MINNEAPOLIS, MINNESOTA, ASSIGNOR TO WILLIAM Z. SCHWAB,
OF MINNEAPOLIS, MINNESOTA.

INDESTRUCTIBLE MARKING DEVICE FOR CASTINGS.

1,251,491.

Specification of Letters Patent

Patented Jan. 1, 1918.

Application filed September 11, 1916. Serial No. 119,442

To all whom it may concern:

Be it known that I, EDWARD FERRISS, a citizen of the United States, residing at Minneapolis, in the county of Hennepin and State of Minnesota, have invented certain new and useful Improvements in Indestructible Marking Devices for Castings; and I do hereby declare the following to be a full, clear, and exact description of the invention, such as will enable others skilled in the art to which it appertains to make and use the same.

My present invention relates to the markings of castings for the identification thereof and has for its object to provide indestructible marking devices that cannot be obliterated by cutting, filing, wearing or other mutilations.

While said invention is adapted to mark all castings requiring identifying characters, it is especially adapted for marking the engine cylinders, chassis, or other parts of a motor-driven vehicle. As is well known, when an automobile is stolen, the thief, before using or offering the same for sale, removes by chiseling or filing all identifying characters cast on the engine cylinders or other parts of the machine, in order to prevent detection.

30 To the above end, the invention consists of the novel devices and combinations of devices hereinafter described and defined in the claims.

In the accompanying drawings, which illustrate the invention, like characters indicate like parts throughout the several views.

Referring to the drawings;

Figure 1 is a fragmentary side elevation of an internal combustion engine cylinder having its identifying character produced by casting therein indestructible marking pins and scale alining posts. The identifying character for the casting is also cast integral therewith in raised numerals and letters;

Fig. 2 is a vertical section taken on the line 2-2 of Fig. 1;

Fig. 3 is a plan view of a templet holding the pins in a relative arrangement indicating the identifying character of the casting shown in Fig. 1 and also holding the scale alining posts;

Fig. 4 is a perspective view of one of the alining posts;

55 Fig. 5 is a perspective view of one of the identifying character pins;

Fig. 6 represents the identifying character produced by the pins, as held by the templet in Fig. 3 and as positioned in the casting shown in Fig. 1;

Fig. 7 is a plan view of the scale for reading the identifying character produced by the pins;

Fig. 8 is a view corresponding to Fig. 1, with the exception that the identifying character is not duplicated and cast integral therewith in raised letters, and has illustrated thereon, by means of broken lines, a straight edge laid on the vertical posts for guiding the scale, shown in Fig. 7, in locating the pins which produce the number of the casting, as represented in Fig. 6; and

Fig. 9 is a view corresponding to Fig. 8, with the exception that the straight edge is laid on the horizontal posts for guiding the scale in locating the pin, which represents the class letter of the casting, as represented in Fig. 6.

The numeral 1 indicates an engine cylinder having the invention incorporated therein. At the time the cylinder 1 is cast, there is cast therein a multiplicity of vertically and horizontally spaced pins 2 and scale alining posts 3. As shown, these pins 2 and posts 3 extend completely through the outer wall of the cylinder 1, so that they cannot be obliterated by cutting or filing.

Before the cylinder 1 is cast, a sufficient number of the pins 2, to indicate the identifying character of the cylinder, are set into the green sand or into the core, at the time the same is made, and thus held during the casting of the cylinder. In order that the pins 2 and posts 3 may be properly positioned in the sand, to clearly and correctly represent the identifying character of the cylinder or other casting, I provide a templet 4. This templet, as shown, has formed therein eleven vertical rows of holes 5. There are seven of these holes in each vertical row and the holes of the eleven rows are in horizontal alinement. The holes 5 in the templet 4 are spaced both vertically and horizontally equal distances apart, as shown. They are one-quarter of an inch between centers.

The first ten vertical rows of holes 5, from the left to the right, are identified, respectively, by the digits 1 to 0 marked on the templet 4 thereabove. The seven holes in the eleventh vertical row are identified, respectively, by the letters A to G, inclusive,

reading from the top down, and said letters are marked on the templet 4 at the right of said row. By thus identifying certain rows of the holes 5 by the digits and certain other 5 of said holes by the letters of the alphabet, the pins 2, positioned by the templet 4, draw their numbers and class letter from the relative positions they occupy. For example, if the pins 2 were set on a quarter inch scale, 10 as shown, the numeral 1 would come within the first quarter and the numeral 2 within the second quarter and so on throughout the digits.

The templet 4 also has formed therein, at 15 its two upper corners and lower left hand corner, holes 6 to receive and hold the scale alining posts 3 to properly position the same in the sand with the pins 2. As shown, these holes 6 for the scale alining 20 posts 3 are located outside of the vertical and horizontal rows of holes 5 and have surfaces that extend parallel to said rows. After the pins 2 and posts 3 are set in the sand, the templet 4 is removed therefrom.

25 To facilitate the reading of the identifying character of a casting produced by the pins 2, there is illustrated in Figs. 7, 8 and 9 a special scale 7. This scale 7 has its upper and right hand edges graduated to the 30 same scale as the spacing of the holes 5 in the templet 4 and said graduations are identified in the same manner as said holes. That is, the horizontal graduations on the 35 scale 7 are indicated by the digits and the vertical graduations by the first seven letters of the alphabet.

In reading the number of the cylinder 1, a straight edge 8, diagrammatically illustrated by means of broken lines, is placed 40 on the two vertical posts 3 (see Fig. 8), and the scale 7 placed against the right hand edge thereof. With the scale 7 in this position, the same is moved downward over the pins 2 underlying the digits and the 45 numerals they represent by the positions they occupy are noted and, as illustrated, read 6492583. To determine the class in which the cylinder 1 comes, the straight edge 8 is placed on the horizontally alined 50 pair of posts 3 (see Fig. 9), and the upper edge of the scale 7 placed against the lower edge thereof. The scale is then moved to carry its right hand edge into alinement with the pin 2 in the eleventh vertical row 55 to determine its position. It will be noted, by reference to Fig. 9, that this pin occupies the third position, which identifies the casting as coming in class—C. From the above, it will be noted that the identifying 60 character of the cylinder 1 is as appears in Fig. 6.

In place of the straight edge 8, lines may

be scratched or marked on the cylinder 1 between the horizontally and vertically alined pairs of posts 3, for the purpose of 65 guiding the scale 7. The reading of the identifying character of a casting may be accomplished with an ordinary rule, when the scale is once known, and this, of course, would be very easy to determine. In order 70 that the pins 2 and posts 3 may be easily distinguished, when the same are cut and finished even with the casting, the same are preferably made of a different material. For instance, if they were wrought iron, 75 they could be easily distinguished from the cast metal.

The cylinder 1, in Fig. 1, has cast integral therewith in raised numerals and letters the identifying character of the cylinder, as 80 represented by the pins 2. This double marking of the cylinder 1 affords, through the raised numerals and letters, easy means for identifying the cylinder and, through the pins 2, identifying means that cannot 85 be destroyed. The pins 2 and posts 3 are represented as round and triangular in cross section, respectively, but it is, of course, understood that they may be made in various different shapes. They may also be made 90 spiral or in other irregular forms to prevent the same from being driven endwise from the casting.

What I claim is:—

1. A casting having cast in the body 95 thereof, a multiplicity of character forming elements in a relative arrangement indicating an identifying character.

2. A casting having cast in the body 100 thereof, a multiplicity of character forming elements in a relative arrangement indicating an identifying character, the said identifying elements being of a metal differing from the casting in character and appearance.

105 3. A casting having cast in the body thereof, a multiplicity of character forming elements in a relative arrangement indicating an identifying character, the said identifying elements being in bifactored arrangement.

110 4. A casting having cast therein, a multiplicity of character indicating elements in bifactored arrangement and having scale alining elements located outside of and parallel with the alined rows in said bifactored elements.

In testimony whereof I affix my signature in presence of two witnesses.

EDWARD FERRISS.
